UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING.

1,357,810.

Specification of Letters Patent.

Patented Nov. 2, 1920.

Application filed September 25, 1919. Serial No. 326,122.

To all whom it may concern:

Be it known that I, JOHN F. O'CONNOR, a citizen of the United States, residing at Chicago, in the county of Cook and State of Illinois, have invented a certain new and useful Improvement in Side Bearings, of which the following is a full, clear, concise, and exact description, reference being had to the accompanying drawings, forming a part of this specification.

This invention relates to improvements in side bearings.

The object of the invention is to provide a side bearing adapted for railway cars wherein the anti-friction element of the bearing is self-centering under the influence of gravity, is non-shiftable, and is provided with a plurality of sets of friction surfaces, any set of which may be brought into use.

20 In the drawing forming a part of this specification, Figure 1 is a part sectional part elevational view of portions of body and truck bolsters of a railway car showing my improvements in connection therewith.

25 Fig. 2 is a vertical sectional view of the side bearing proper taken substantially on the line 2—2 of Fig. 1. Fig. 3 is an elevational view of a side bearing similar to that shown in Fig. 1 but illustrating a somewhat different construction. Fig. 4 is a sectional view

30 corresponding to Fig. 2 taken on the line 4—4 of Fig. 3. And Fig. 5 is a detail perspective of one of the guiding arms employed in the construction illustrated in

35 Figs. 1 and 2.

Referring first to the construction illustrated in Figs. 1, 2 and 5, 10 denotes the under side of a body bolster, and 11 the upper side of a truck bolster to which my improved side bearing is preferably attached. The side bearing, as shown, consists, broadly, of three elements, a housing or retaining member or base casting A, an anti-friction element B, and separable counter-balancing guide arms C—C.

40 The base casting A, as shown, is of substantially hollow box-like form having parallel spaced side walls 12, 12, curved end walls 13—13, a bottom bearing wall 14, and 45 perforated corner lugs 15 by which it is adapted to be riveted or otherwise secured to the bolster. Openings 16 are formed in the side walls to permit dirt and other foreign material to be washed out. Also, 55 the side walls 12 are provided with lateral

integral offsets indicated at 17—17, the latter having guiding faces 18—18 on the interior thereof which slope upwardly and away from the center of the bearing, as viewed in Fig. 1. At the tops of the guiding 60 surfaces 18, inturned rounded shoulders 19—19 are provided and between the shoulders 19 an entrance opening 20 is provided to admit the arms C—C hereinafter described. Said lateral extensions 12 of the 65 base casting are extended above the general top level of the base casting, as clearly indicated in Fig. 1, and at their upper ends said offsets are perforated to accommodate long retaining cotters 21.

70 The anti-friction element B is of substantially triangular form in end elevation and is formed with three sets of concentric bearing surfaces of different radii, the same being referenced 22—22^a; 23—23^a; and 24—24^a. With this construction, it is evident that the element B is symmetrical, and, consequently, any set of the concentric bearing surfaces may be utilized by adjusting the member B so as to bring the proper bearing 75 surface 22, 23 or 24 at the bottom. In this manner, after one set of bearing surfaces has been utilized and worn, the other sets may be brought into use successively to thereby prolong the life of the bearing.

80 While the anti-friction element B, as shown, is of the rocker type and will return to a balanced position under the influence of gravity, nevertheless, it is desirable to provide means for positively preventing bodily 85 shifting of said element B with respect to the base casting A. This function is performed by the pair of arms C, each of the latter being in the form of a plate, indicated at 25, of a shape hereinafter described, and 90 a triangular lug 26. The triangular lugs 26 are arranged to fit snugly within triangular sockets 27 provided in the ends of the element B, so that, while the arms C are normally rigid with respect to the element B, 95 100 nevertheless, they may be adjusted to any one of three positions, in accordance with the particular set of concentric bearing surfaces which is being employed at the time.

105 Each plate 25 is relatively wide near its bottom and the edges are gradually brought together toward the top so as to provide a tapered or wedge shaped upper end indicated at 28. The maximum width of the plate 25 corresponds substantially to the dis- 110

tance transversely between the guiding surfaces 18-18 between which the plate is received, so that the plate, and, consequently, the element B, can not be shifted bodily 5 more than a predetermined distance, according to the slight clearance left between the edges of the plate C and the guiding surfaces 18. The exact contour of the edges of the plates 25 is made such that the distance, horizontally, across the plate in any 10 angular position of the latter, will correspond substantially to the horizontal distance between the guiding surfaces 18 at the same level. With this construction, it is evident that the element B is free to rock, while, 15 at the same time, the plates of the arms C prevent the element B from becoming displaced and the latter must return to its central normal position under the influence 20 of gravity after each actuation. It will also be noted that the arms C assist in returning the element B to normal since they act in the nature of counter-balances which are necessarily elevated as the element B is 25 rolled to either side of normal position.

In the construction illustrated in Figs. 3 and 4, the same principles are employed, the housing or base casting being designated as A', the anti-friction element as B', and the 30 guiding arms as C'. The arms C' are made adjustable with respect to the rocker B', as described in connection with the construction shown in Figs. 1, 2 and 5. Substantially the only difference is in making the bottom 35 wall 114 of the base casting separate from the main part thereof and making the laterally offset guiding recesses closed at their tops by integral walls 121 instead of by employing the cotters 21 for holding the 40 parts in assembled relation. In the construction shown in Figs. 1 and 2, the anti-friction element is inserted from the top, after which the cotters 21 are inserted, while in the construction shown in Figs. 3 and 4 the anti-friction 45 element is inserted from the bottom and the bottom wall 114 inserted after the anti-friction element. In this construction the parts will be held assembled when the base casting is riveted to the bolster. Also, 50 a slightly different configuration for the arms C' is shown than that for the arms C, which in turn necessitates a slightly different contour for the guiding recesses co-operating therewith, but the principle of determining the relation between the plates of 55 the guiding arms and the recesses is the same as that described for the construction shown in Figs. 1 and 2.

I claim:

60 1. In an anti-friction bearing of the character described, the combination with a hollow retaining member adapted to be secured to a bolster and provided with a flat horizontal bearing seat, of an anti-friction element disposed within said member and hav-

ing concentric upper and lower bearing surfaces, said element being adapted for rolling movement along said seat, and a centering arm rigid with respect to said element, said retaining member having a guiding recess co-operable with said arm to insure the return of said element to its normal central position upon removal of the actuating pressure, said guiding arm being adjustably connected to the anti-friction element. 70

2. In an anti-friction bearing of the character described, the combination with a retaining member having a bearing seat, of an anti-friction element adapted to roll on 80 said seat in either direction from normal, a centering member rigid with respect to said element and adapted to be elevated when said element is rolled to either side of normal, said retaining member having 85 guiding surfaces co-operable with said centering member said centering member being detachable with respect to the anti-friction element and attachable to the latter in different positions. 90

3. In an anti-friction bearing of the character described, the combination with a retaining member, of an anti-friction element, said member having a bearing seat horizontal throughout and on which said element bears and is adapted to roll to either side of normal position, said element having an eccentrically disposed arm rigid with respect thereto and adapted to be elevated when the element is rolled from its 100 normal position, said retaining member having guiding surfaces co-operable with said arm to prevent bodily shifting of said element with respect to the retaining member, said arm and element being separately 105 formed and adapted for rigid connection in different angular relations.

4. In an anti-friction bearing of the character described, the combination with a retaining member, of a rocker bodily movable 110 within said member, said rocker having a plurality of sets of concentric bearing surfaces of different radii, and an arm rigidly attached to said rocker, said member having a guide to accommodate said arm, said arm being adjustably attachable to the rocker in a number of positions corresponding to the 115 number of sets of bearing surfaces.

5. In an anti-friction bearing, the combination with a hollow housing having a 120 bearing surface therein, of a gravity self-returning rocker disposed within said member, said member having guiding recesses opposite the ends of the rocker, said rocker having guiding arms rigidly attached 125 thereto at its ends and working in said recesses, said arms being detachable from the rocker without destructive effect when the rocker is dis-assembled from the housing. 130

6. In an anti-friction bearing, the com-

bination with a hollow retaining member adapted to be secured to a bolster, of a rocker disposed within said retaining member, said rocker having a plurality of sets of concentric bearing surfaces of different radii, and a combined centering and guiding arm detachably connected to said rocker and adjustable to different positions with respect thereto according to the number of sets of bearing surfaces.

7. In an anti-friction bearing, the combination with a hollow base casting adapted to be secured to a bolster, of a self-returning gravity rocker disposed within said

base casting, said rocker having a plurality of sets of concentric bearing surfaces of different radii and guiding arms rigidly attached to the rocker at the ends thereof, said guiding arms being adjustable to different positions relatively to the rocker in accordance with the number of sets of bearing surfaces thereof, said base casting having guiding surfaces in the side walls thereof coöperable with said arms.

In witness that I claim the foregoing I have hereunto subscribed my name this 8th day of Sept. 1919.

JOHN F. O'CONNOR.
